INVERTED WELL PACKER

Filed Sept. 19, 1949

UNITED STATES PATENT OFFICE

2,649,158

INVERTED WELL PACKER

Frank A. Reed, Butler, Pa.

Application September 19, 1949, Serial No. 116,536

1 Claim. (Cl. 166—12)

1 This invention relates to an improved packer for holding and sustaining air, gas or water pressures in an injection or input well for secondary recovery drives, and for fluid disposal wells, or it may be used as a plugging device against pressures in the lower part of a well or as a device for transmitting various plugging agents into permeable oil, gas or water strata under sustained pressure.

The purpose of this invention is to provide an inverted well packer wherein one section may be removed at a time so that it is readily releasable and may readily be removed from the well.

Heretofore, it has been found necessary to cement the packer and injection string in the well in order to hold internal pressures. There are conditions in a well where, due to various obstacles and cavings from other strata, where an up-side-down packer will not release and this plugs up the body slots of the packer and prevents the release thereof. With this thought in mind this invention contemplates an up-side-down packer in which it is possible to remove one section at a time when it is impossible to remove the packer by conventional methods. This improved packer also enables operators to hold the internal pressures by utilizing pressures in the lower part of a well as a force applied to further setting of the packer.

The object of this invention is therefore to provide means for constructing a well packer whereby it is adapted for use in an inverted position and whereby the packer is readily releasable so that it may be removed.

Another object of the invention is to provide an up-side-down packer having an L-shaped slot therein and in which the body pin may be rehooked into the L-shape slot to facilitate removal of the parts.

A further object of the invention is to provide an improved up-side-down slip packer that is readily releasable and which is of a comparatively simple and economical construction.

With these and other objects and advantages in view the invention embodies an up-side-down packer having a connecting pipe threaded on the upper end to conform to the injecting string and with the lower end threaded with left hand threads into the extensible member and with the extensible member actuated by a slip assembly having an L-shaped slot therein with a corrugated upper end and wherein manipulation of the slip assembly is controlled by the body pin in the L-shape slot.

Other features and advantages of the inven-

2 tion will appear from the following description taken in connection with the drawings wherein:

Figure 1 is a vertical section through the unit with parts illustrated in the free positions.

Figure 2 is a cross section through the unit, taken on line 2—2 of Figure 1.

Figure 3 is a detail showing a section of the body of the unit illustrating the position of the body pin in the L-shaped body slot.

Figure 4 is a detail showing a vertical section through the lower end of the unit, and showing a modification wherein the inner surface of the bushing in the head is smooth.

Referring now to the drawings wherein like reference characters denote corresponding parts the inverted or up side down well packer of this invention includes a pipe or injecting string 10, a rubber sleeve 11 providing an extensible unit, a head 12 under which the lower end of the pipe 10 is threaded, wall gripping slips 13, a body sleeve 14 surrounded by a slip sleeve having an L-shaped slot 15 therein, and a body pin 16.

The upper end of the pipe 10 is provided with right hand threads 17 and the lower end is threaded into the head 12 with left hand threads 18. By this means the pipe may readily be unscrewed from the head 12 without disconnecting the upper parts thereof.

The slip assembly includes a collar 19 having an upwardly extended sleeve 20 with corrugations or serrations 5 in the outer surface thereof and an outer body sleeve 21 which is threaded into the lower end of the collar 19 with threads 22 and on the lower end of which the slips 13 are provided. The outer body sleeve 21 extends downwardly from the collar 19 and two sets of latch spring members which provide frictional wall engaging elements are positioned thereon. The L-shaped slot 15 is provided in the outer or slip sleeve 21 and the lower end of the slot is provided with a horizontal section 23. The body pin 16 is positioned in the horizontal section 23 as the unit is inserted into and removed from a well.

The slips 13 are formed on the lower end of the outer sleeve 21 and the slips are formed with beveled inner surfaces 24 and serrated outer surfaces 25. The lower ends of these slips spring outwardly as shown in Figure 1 in the free position.

The slips 13 are resiliently held inwardly by frictional well wall engaging means comprising springs 26 which are mounted on the outer sleeve 21 at the points 27 and the beveled surfaces 24 ride upon the frusto-conical surface 28 of a collar

3

29 on the outer surface of the body sleeve 14. The tip of a collar 29 is held against a shoulder 30 on the body sleeve 14 by the rubber sleeve 11 with the parts in the free position.

The rubber sleeve 11 is positioned between the collar 29 and the head 12 with a ferrule 31 carried in the lower end of the rubber sleeve and secured by threads 32 on the head. The head 12 is threaded on the lower end of the body sleeve 14 with threads 33, and the head is connected to the end of the pipe or string 10 through a bushing 34 having a threaded lower end 35 that is screwed into the head 12. The inner surface of the lower end of the bushing 34 is provided with threads 36 and the left hand thread 18 into which the lower end of the string 10 is screwed are provided in the upper end. It will be understood that the threads 36 in the inner surface of the lower end of the bushing may be omitted as shown in Figure 4, if desired. The bushing is secured in the head by a set screw 37. The upper end of the body sleeve 14 is provided with a sleeve 38 having a flange 39 around the intermediate part thereof and the lower end is connected to the sleeve 14 with threads 49. The outer surface of the upper end of the sleeve 38 is provided with corrugations or serrations 41, as shown.

The body pin 16 is provided with a head 42 and a spring 43 is positioned on the pin between the head and inner surface of the sleeve 14, as shown in Figure 2. The pin 16 is slidably mounted in an opening 44 in the body sleeve 14 and the outer end extends into the L-shaped slot 15 of the sleeve 21.

The upper part of the outer sleeve 21 may also be provided with frictional well wall engaging means comprising springs 45 that are attached to the sleeve at the point 46. The upper end of the string 10 may be provided with a coupling 47.

In the modification illustrated in Figure 4 a bushing 48, similar to the bushing 34, is threaded into the lower end of the head 12 through the threads on the outer surface of the lower ends 49 thereof and the upper end is provided with left hand threads to correspond with the left hand threads 18 of the pipe 10. In this design the inner surface 50 of the lower end of the bushing is smooth instead of being provided with threads such as the threads 36.

The lower end of the head 12 is provided with a beveled inner surface 51 as shown.

With the parts arranged in this manner the packer is strung up ready to run into the hole and before it is run into the hole it should be examined to see that the pin 16 is all of the way over in the horizontal part 23 of the L-shaped slot 15. The pin should remain in this position while the packer is being lowered into the well.

When packer is in position in the well and ready for setting, the pipe or tube 10 is turned to the left to move the pin 16 into the vertical section of the L-shaped slot 15. The spring assembly including the springs 26 and 45 engage the wall of the well, holding the assembly stationary while the tubing is pulled upwardly with the collar surface 28 engaging the serrated slips 13, the collar being initially mov-

able upwardly with its upper end engaging the shoulder 30 on the body sleeve and as these slips move outwardly and grip the inner surface of the well upward movement of the collar is checked so that with continued upward movement of the head 12 by the string or tube 10 the rubber tube 11 is compressed and bulges outwardly against the wall of the well.

The fluid used for pressuring or for other purposes is then introduced into the tubing and conducted to the bottom of the hole and as the internal pressure increases the tighter the rubber sleeve holds in the well.

When it is desired to remove the packer the string or tube 10 is lowered a little below the point to which it was lowered originally and the tube is then turned to the right whereby the pin 16 is moved backwardly across the horizontal part of the L-shaped slot. Should it be impossible to remove the packer by pulling the tubing, the tubing is then turned to the right unscrewing the tube in the left hand thread 18 whereby the tube 10 may be removed and as the end of the tube passes the pin 16 the pin will drop into the well. A combination socket may then be run into the well to engage the serrations on the collar 19 whereby the slip assembly may first be removed and then the lower part of the packer assembly including the body sleeve and head may be removed.

It will be understood that other modifications may be made in the design and arrangement of the parts without departing from the spirit of the invention.

35 What is claimed is:

In an inverted well packer, the combination which comprises a vertically disposed connecting tube threaded at its upper end, a head threaded on the lower end of said connecting tube, a body sleeve positioned around and spaced from said connecting tube, a slip sleeve having an L-shaped slot therein positioned around said body sleeve, a body pin carried by said body sleeve and extended into said L-shaped slot of the slip sleeve, an extensible sleeve extended around said body sleeve and positioned with the lower end resting upon said head, a collar having a frusto-conical shaped upper end extended around the body sleeve and positioned on the upper end of the extensible sleeve, slips carried by said slip sleeve and positioned to be expanded by said collar, vertically spaced sets of outwardly bowed springs secured at one of the ends thereof to the surface of the slip sleeve, and a collar carried by the upper end of the slip sleeve and slidably mounted on the connecting tube, said collar having serrations in the outer surface of the upper end.

FRANK A. REED.
